(57) **CLAIM**

The ornamental design for a combined toilet seat and cover, as shown and described.

DESCRIPTION

FIG. 1 is a front view of a combined toilet seat and cover, showing our new design.

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is a perspective view of the combined toilet seat and cover in an alternate configuration.

The broken lines in the drawings depict portions of the combined toilet seat and cover that form no part of the claimed design.
